SAFETY MATCH PACKET

Oliver P. Pindell, Columbus, Ohio

Application August 10, 1936, Serial No. 95,078

3 Claims. (Cl. 40—126)

This invention relates to improvements in the packaging of paper safety matches and has particular reference to a novel type of package wherein provision is made for increasing the appeal and to stimulate the curiosity of the user of such a package as to the nature of certain advertising or printed matter appearing on the matches or the paper covers therefor.

Safety matches composed principally of paper are now quite widely used by smokers of tobacco products and are quite commonly distributed gratis to the purchasers of such products. Most of these paper matches bear on the cover flaps, as well as on the matches themselves, printed advertising matter which is a factor in enabling dealers in tobacco products to distribute such matches free of charge to their customers.

It is an object of the present invention to increase the advertising appeal and available advertising area of such paper matches by providing one or more of the cover flaps thereof with colored translucent windows which may be positioned in registration with indicia of any desired character printed on the matches of the packet, or on special sheets provided for that purpose, in two or more contrasting primary colors whereby a single surface, bearing such indicia may contain a plurality of messages or designs, which may be selectively viewed by presenting the colored translucent or transparent panels in registration therewith. Thus a design printed in red ink may be readily viewed through a green panel and, conversely, a design printed in green ink may be clearly viewed by presenting the red panel.

It is thus another object of the invention to provide a packet of paper matches wherein a plurality of messages or designs are provided upon a single surface, and to render such messages or designs selectively visible by the provision of flap carried panels of such coloration that when one of said panels is placed over said surface, one of such designs or messages may be viewed and understood and when another of said panels is placed over the indicia bearing surface, the other of said messages or designs will become viewable.

For a further understanding of the invention, reference is to be had to the following description and the accompanying drawing wherein:

Fig. 1 is a perspective view of a packet of paper matches formed in accordance with the present invention;

Fig. 2 is a similar view disclosing the front

panel-carrying flaps of the packet in an open position:

Fig. 3 is a transverse horizontal sectional view taken on the plane indicated by the line III—III of Fig. 2;

Fig. 4 is a vertical transverse sectional view on the plane indicated by the line IV—IV of Fig. 1;

Fig. 5 is a front elevation disclosing a design appearing on one of the indicia bearing surfaces 10 of the packet when viewed through one of the flaps;

Fig. 6 is a similar view showing said surface when viewed through the other of said flaps;

Fig. 7 is a perspective view of a modified form 15 of the invention;

Fig. 8 is a similar view of a still further modified form.

Referring more particularly to the drawing, and especially to the form of the invention disclosed in Figs. 1 to 6 inclusive, a packet of paper matches is indicated at 1. The packet comprises a paper cover formed to include integral back, side and bottom walls 2, 3 and 4 respectively, the bottom wall terminating along its forward edge in a short upstanding abrasive receiving wall 5. Also, integrally formed with the forward edges of the side walls 3 are pivotally or hingedly movable front walls or flaps 6, each of which possesses a width substantially equal 20 to that of the back wall 2, the said flaps extending from the upper edge of the wall 5 to the top of the packet. In this instance, the packet contains three parallel rows *a*, *b* and *c* of upright paper matches 7, the said rows being spaced by 25 separating sheets 8. The matches 7 and the sheets 8 are preferably held in the packet by means of a metallic staple 9 which passes through the wall 5, the lower base portions of the matches 7, the sheets 8 and are clinched upon the back 30 wall 2, thereby holding the several parts of the packet together.

In carrying out the invention, advertising matter or other forms of printed indicia, disclosed at 10 are printed in contrasting primary colors 45 on the front surface of each row of the matches 7 and also on the separating sheets 8. Thus, two or more messages may be applied to each of these surfaces. These messages are separately viewable by providing the flaps 6 with 50 openings 11, which are covered by means of substantially transparent or translucent panels 12 and 12' which correspond in dimensions to the indicia 10 on each of the aforementioned surfaces. Thus as shown in Fig. 6, when the flap 55

carrying the panel 12 is closed, that is, when the panel 12 is brought into registration or juxtaposition with the indicia 10 appearing on the matches 7 or the sheets 8, the design or indicia indicated at 13 in Fig. 6 will be viewable.

For instance, should the panel 12 possess a green color, the indicia 10 printed in red will be viewable. Again, as shown in Fig. 5, should the flap 6 bearing the panel 12' be brought into registration with said indicia containing surfaces, the design indicated at 14 will be rendered visible. This may be done by coloring the panel 12' red, so that the message printed in green on the match and sheet surfaces may be rendered clearly discernible. From an advertising standpoint, it will be seen that after the row of matches a has been completely utilized, the message on the front sheet, normally disposed between the rows of matches a and b, may be brought into registration with the panels 12 and 12'. When this sheet is torn from the packet, a message printed on the front surface of the row b of matches may then be utilized and after this row has been exhausted, the second sheet, normally positioned between the rows b and c of matches, will be presented to view. When the second separating sheet is torn out, or otherwise removed from the packet, the indicia appearing on the front surfaces of the matches comprising the row c may be registered with the panels 12 and 12'. By this construction, each packet of matches may contain a maximum amount of advertising or other forms of printed publicity matter, and in addition, the packet will embody an element of novelty and mechanical appeal which will stimulate the curiosity of the user and compel greater reading and notice of the printed messages contained on the several pads of the packet. The construction is economical and may be thrown away after use. However, in a variation of my invention, the matches and the sheets 8 may be removably received within the cover section and the latter thus rendered adaptable for more extended and permanent use, matches being supplied thereto in the form of a "re-fill".

By the provision of the separating sheets 8, the user is induced to complete the use of one layer of matches before commencing use of a

new layer, thus maintaining the printed indicia on the under layers complete until it is observed through the panels 12 and 12'.

Another variation of my invention has been disclosed in Fig. 7 wherein the paper packet of matches indicated at 15 is of conventional configuration with the exception that there is provided a pair of front flaps 16 and 17 which constitute integral extensions of the back wall 2a of the packet. The flap extensions 16 and 17 are provided with the contrastingly colored transparent translucent panels 12 and 12'. Similarly, in Fig. 8, the flap 17' is integrally formed with the upper portion of the abrasive receiving wall 5a, while the flap 16' forms an integral continuation of the back wall 2b.

What is claimed is:

1. A paper match packet comprising a cover having a back and a pair of relatively movable front sections, a group of paper matches flatly arranged within said cover and bearing on their outer surfaces indicia printed in contrasting primary colors, and substantially transparent or translucent panels of corresponding color positioned in registration with openings formed in the movable front sections of said cover and disposed for selective juxtaposition with the indicia appearing on said matches.

2. In a packet of paper matches, a pair of relatively movable cover sections, and divided color panels of a substantially transparent material carried by said sections and disposed for registration with advertising indicia printed in contrasting primary colors on other surfaces of said packet.

3. A paper match packet comprising a cover having a back and a pair of relatively movable front sections, a plurality of rows of paper matches arranged within said cover, spacing sheets between adjoining rows, said rows of matches and said spacing sheets bearing a plurality of messages printed in contrasting colors and in overlapping relationship, and substantially transparent or translucent panels of corresponding colors carried by said front sections and disposed for selective registration with said messages.

OLIVER P. PINDELL.
